UNITED STATES PATENT OFFICE.

EDGAR J. LUTWYCHE, OF CHICAGO, ILLINOIS, ASSIGNOR TO CHARLES H. REYNOLDS,
OF CHICAGO, ILLINOIS.

LAMP.

13,630.

Specification of Reissued Letters Patent. Reissued Oct. 21, 1913.

Original No. 1,070,383, dated August 12, 1913, Serial No. 726,977. Application for reissue filed August 28, 1913. Serial No. 787,233.

To all whom it may concern:

Be it known that I, EDGAR J. LUTWYCHE, a citizen of the United States, residing at Chicago, in the county of Cook and State of Illinois, have invented certain new and useful Improvements in Lamps, of which the following is a specification.

This invention relates to that class of lamps which are used in connection with automobiles and other motor vehicles, a lamp of this kind being disclosed and claimed in my prior Patent No. 1,022,589, dated April 9, 1912, and the present invention being an improvement thereof.

15 It is the object of the present invention to provide a novel construction and assemblage of parts whereby a more rigid and durable lamp is had, and also to provide a structure which permits ready removal of 20 the lens, and adjustment of all of the parts of the lamp.

The invention also has for its object to provide novel means for securing the lamp to a supporting bracket.

25 In order that the invention may be better understood, reference is had to the accompanying drawing, in which—

Figure 1 is an elevation of the lamp, and Fig. 2 is an enlarged horizontal section on 30 the line 2—2 of Fig. 1.

As in my patent hereinbefore referred to, the casing 5 of the lamp is preferably made of glass and is in one piece. Within the casing is mounted a parabolic reflector 6, 35 which may be of glass, having at its forward end or periphery a curved rim 7, which abuts against the corresponding open end of the casing. Around the abutting parts fits a ring which is angular in cross-section. One 40 of the parts 8, of the ring fits on the outside of the casing 5, and extends across the joint between the same and the rim 7, and the other part 9, of the ring extends around in front of said rim. The part 8, of the ring 45 has a bead 10, forming a channel in which seats a bead 11, formed on the outer surface of the casing, said channel and bead serving to hold the ring in place on the casing.

50 The front of the casing is closed by a glass 12, carried by a hinged frame consisting of a ring 13, to which are soldered or otherwise secured retaining fingers 14, which grip the glass near its periphery and hold

the same securely to the ring. The ring 13, 55 is connected by a hinge 15, to the part 8, of the ring hereinbefore described, and said part, diametrically opposite the hinge, also carries an outstanding screw-threaded stem 16, which is adapted to be engaged by a 60 pivoted latch-hook 17, carried by the ring 13. A nut 18, screwed on the stem, over the latch-hook, prevents disengagement of the latter. Upon unscrewing the nut, the latch can be slipped off the stem, and the glass can 65 then be swung open. The hinge 15, may be soldered on the part 8.

In the embodiment of the invention illustrated in the drawing, the center or rear end of the reflector 6, has a reduced neck 19, lying wholly in the space between the reflector and casing, and the center or rear end of the casing 5, terminates in a reduced neck 22. A connection or support is provided between the rear ends of said reflector and casing, and said connection or support is here 70 shown as adjustably connected with the casing for the purpose of drawing the peripheral rim 7, of the reflector against the adjacent forward edge of the casing. One 75 form of such connection or support is here shown as comprising a tubular member or sleeve 20, connected to the reflector, as for instance by cementing the neck of the reflector in the tubular member or sleeve, said 80 sleeve having a rearwardly extending portion 21, extending through the neck 22, of the casing and capable of being secured to the casing in an adjustable manner. One 85 form of connection between the casing and tubular member 20, may comprise a threaded connection between the portion 21, of the tubular member and the sleeve 22, of the casing. By this assemblage of parts the reflector and the casing may be brought together 90 until the rim 7, abuts against the edge of the casing as hereinbefore described. A small cap 23, is screwed on the neck 22, over the outer end of the latter and the 95 part 21.

In the neck 19, of the reflector 6, is slidably mounted a socket-piece 24, into which the lamp base 25, screws. From the back of the socket-piece extends a stem 26, which passes through the part 21, and is threaded 100 to screw through the back of the cap 23, which is thickened to provide sufficient metal for the threaded aperture through which the 105

stem passes. At the outer end of the stem is a head 27, which serves as a finger hold. The purpose of the stem is to adjust the socket-piece 24, lengthwise in the sleeve 20, which is readily done by rotating the stem. The cap 23, and the back of the socket-piece 24, are also apertured for the current wires W of the lamp. When a sleeve having a reduced extension is employed a rubber gasket 10 is interposed between the back of the part 20, and casing.

At diametrically opposite points, the casing 5, carries a device for mounting the lamp on a bracket. Each of these devices 15 comprises a socket-piece 29, having a stem 30, which passes through an aperture in the casing 5. That end of the stem which projects into the casing is threaded to receive a nut 31. The aperture in the casing 20 through which the stem passes is lined with a rubber bushing 32, which latter also extends between the base of the socket-piece 25 and the outer surface of the casing, and between the inner surface of the casing and 30 a fiber washer 33, mounted on the projecting end of the stem. The nut 31, is screwed against this washer. The outer surface of the casing has a bead 34, which surrounds the base of the socket-piece and thus forms 35 a seat therefor.

By the devices herein described the socket-pieces 29, are rigidly fastened to the casing 5, and there is no danger of injury to the latter. The stems 35, of the lamp bracket 35 are secured in the socket-pieces by set screws 36.

More or less variation of the exact details of construction is possible without departing from the spirit of this invention and I 40 do not therefore desire to limit myself to the exact details of construction, except as may be necessitated by the prior state of the art.

I claim as new and desire to secure by 45 Letters Patent:

1. A lamp comprising a casing having at its rear end a centrally located reduced neck, an open front reflector in the casing and having a peripheral rim abutting against 50 the forward end of the casing, said reflector also having a centrally located reduced neck at its rear end terminating in the space between the casing and reflector, and a tubular support connected to the reflector and 55 extending from its neck to and through the neck of the casing, said tubular support having an adjustable connection with respect to the casing for drawing together said rim and forward end of the casing.

60 2. A lamp comprising a casing member having at its rear end a centrally located opening, an open front reflector member in the casing and having a peripheral rim abutting against the forward end of the casing, said reflector also having a centrally 65

located opening at the rear thereof, spaced away from the opening of the casing, and connecting means between the rear ends of said casing and reflector for holding together the forward end of the casing and 70 rim of the reflector, said connecting means extending through the opening in one of said members and thereat secured to said member.

3. A lamp comprising a casing member 75 having at its rear end a centrally located opening, an open front reflector member in the casing and having a peripheral rim abutting against the forward end of the casing, said reflector also having a centrally located opening at the rear thereof, spaced away from the opening of the casing, and a tubular support connected to the reflector and extending to and through the opening in the casing, said support having an adjustable connection with the casing for drawing together 80 the forward end of the casing and peripheral rim of the reflector.

4. A lamp comprising a casing, a reflector in the casing and having a peripheral 85 rim abutting against the forward end of the casing, and a tubular member connected to the reflector and having an adjustable connection with the casing for drawing said rim and forward end of said casing together. 90

5. A lamp comprising a casing having at its rear end a reduced neck, a reflector in the casing having a peripheral rim abutting against the forward end of said casing, said reflector also having a reduced neck at its 95 rear end, and a tubular member connected to said reflector at the neck thereof and extending through the neck of said casing, said tubular member being provided with means 100 engaging the neck of the casing for holding together said rim of the reflector and forward end of the casing.

6. A lamp comprising a casing, a reflector in the casing and having a peripheral rim 110 abutting against the forward end of the casing, a ring overlapping the joint between said rim and the casing, and having a portion which extends in front of the rim, and a tubular support connecting the center or rear ends of the casing and reflector. 115

7. A lamp comprising a casing, a reflector in the casing and having a peripheral rim abutting against the forward end of the casing, a ring overlapping the joint between 120 said rim and the casing, and having a portion which extends in front of the rim, and a tubular support connected to the reflector and having an adjustable connection with the casing for drawing together the forward end of the casing and rim of the reflector.

8. A lamp comprising a casing having at its rear end a reduced neck, a reflector in the casing and having a peripheral rim abutting against the forward end of the casing, and said reflector also having a cen- 125

tral reduced neck, and a sleeve in which the last mentioned neck is secured, said sleeve having an adjustable connection with the neck of the casing.

5 9. A lamp comprising a casing having at its rear end a reduced neck, a reflector in the casing and having a peripheral rim abutting against the forward end of the casing, and said reflector also having a central reduced neck, and a sleeve in which the last mentioned neck is secured, said sleeve having a reduced threaded portion which screws into the neck of the casing.

10 10. A lamp comprising a casing having at its rear end a reduced neck, a reflector in the casing and having a peripheral rim abutting against the forward end of the casing, and said reflector also having a central reduced neck, a sleeve in which the last mentioned neck is secured, said sleeve having an adjustable connection with the neck of the casing, a socket-piece mounted in the neck of the reflector, and a source of light mounted in the socket-piece.

15 11. A lamp comprising a casing having at its rear end a reduced neck, a reflector in the casing and having a peripheral rim abutting against the forward end of the casing, and said reflector also having a central reduced neck, a sleeve in which the last mentioned neck is secured, said sleeve having an adjustable connection with the neck of the casing, a socket-piece mounted in the neck of the reflector and adjustable lengthwise therein, and a source of light mounted in the socket-piece.

20 12. A lamp comprising a casing having at its rear end a reduced neck, a reflector in the casing and having a peripheral rim abutting against the forward end of the casing, and said reflector also having a central reduced neck, a sleeve in which the last mentioned neck is secured, said sleeve being connected to the neck of the casing, a cap 25 over the outer end of the sleeve and the

neck of the casing, a socket-piece mounted in the neck of the reflector, a stem extending from the socket-piece and screwing through the cap, and a source of light in the socket-piece.

50

13. A lamp comprising a casing, a reflector in the casing and having a peripheral rim abutting against the forward end of the casing, and a support connected to the reflector and having a screw-threaded engagement with the casing for drawing said reflector rim and the forward end of the casing together.

55

14. A lamp casing having an aperture, a socket-piece having a threaded stem extending through the aperture and projecting into the casing, the outer surface of the casing having a bead which extends around the base of the socket-piece, and a nut screwed on the projecting end of the stem.

60

15. A lamp casing having an aperture, a socket-piece having a threaded stem extending through the aperture and projecting into the casing, the outer surface of the casing having a bead which extends around the base of the socket-piece, a nut screwed on the projecting end of the stem, a washer under the nut, and a bushing in the aperture between the outer surface of the casing and the base of the socket-piece, and between the inner surface of the casing and the washer.

70

16. A lamp comprising a casing, a reflector in the casing and having a peripheral rim abutting against the forward end of the casing, and a ring overlapping the joint between said rim and the casing, and having a portion which extends in front of the rim into engagement therewith.

75

In testimony whereof I affix my signature in presence of two witnesses.
